ROCKING REINDEER

Robert J. Grant, Van Nuys, Calif.

Application August 3, 1953, Serial No. 26,249

Term of patent 14 years

(Cl. D34—15)

To all whom it may concern:

Be it known that I, Robert J. Grant, a citizen of the United States, residing at 16760 Saticoy Street, Van Nuys, in the county of Los Angeles, State of California, have invented a new, original, and ornamental Design for a Rocking Reindeer, of which the following is a specification, reference being had to the accompanying drawing, forming a part thereof.

Fig. 1 is a top plan view of a rocking reindeer, showing my new design;

Fig. 2 is a side elevational view thereof, a portion thereof being broken away with a cross bar shown in section;

Fig. 3 is a bottom plan view thereof;

Fig. 4 is a front elevational view thereof; and

Fig. 5 is a fragmentary cross sectional view thereof taken on the line 5—5 in Fig. 2.

The drawing is shaded to indicate the color red for the nose of the animal figure embodied in the design.

I claim:

The ornamental design for a rocking reindeer, as shown and described.
